G. TERRY.
COMBINING SPRINGS FOR MOTIVE POWER.
No. 40,866. Patented Dec. 8, 1863.

Inventor:

George Terry

UNITED STATES PATENT OFFICE.

GEORGE TERRY, OF NEW YORK, N. Y.

IMPROVEMENT IN COMBINING SPRINGS FOR MOTIVE POWER.

Specification forming part of Letters Patent No. 40,866, dated December 8, 1863; antedated October 3, 1863.

To all whom it may concern:

Be it known that I, GEORGE TERRY, of the city, county, and State of New York, have invented a new and useful arrangement of springs for clocks and for other purposes where used as a motor; and I do hereby declare that the following is a full, clear, and exact description of the same, reference being had to the accompanying drawings, making a part of this specification, in which—

Figure 1 is an end view of my invention; Fig. 2, a plan or top view of the same; Fig. 3, a longitudinal section of the same, taken in the line *x x*, Fig. 1.

Similar letters of reference indicate corresponding parts in the several figures.

This invention consists in combining a series of springs—two or more—in such a manner that their strength will be exerted or applied to one and the same shaft, and the latter operated a length of time equal to the capacity or strength of an individual spring, multiplied by the whole number used—that is to say, if three seven-day-clock springs be combined according to my invention, the combined springs will run twenty-one days, and may be applied to a seven-day clock so as to convert the same into a twenty-one-day clock without changing or altering the gearing of the former.

A represents a shaft, which is fitted in a suitable framing, B, and which has placed loosely upon it two disks or plates, C C', provided, respectively, with hubs *a a'*, as shown in Fig. 3.

D represents a coil-spring, the inner end of which is attached permanently to the axle A, and the outer end of said spring attached to an arm, b, which is secured to the disk or plate C, near its edge.

E represents a coil spring, the inner end of which is attached permanently to the hub *a* of the disk or plate C, the outer end of said spring being attached to an arm, c, which is secured to the disk or plate C', near its edge.

F is a coil-spring, the inner end of which is attached to the hub *a'* of the disk or plate C', and the outer end attached to the framing B, as shown at *d* in Fig. 2. The shaft A has its bearings in plates *e e'*, the two former being at the ends of the framing. These plates are connected by rods *f*, to one of which the outer end of the spring F is attached. On one end

of the shaft A there is fitted a ratchet, G, into which a pawl, H, catches. (See Fig. 1.)

From the above description it will be seen that when the shaft A is turned in a direction to wind up the springs the spring D will be acted upon directly by the shaft A, the spring E acted upon from the spring D, through the medium of the disk or plate C and its hub *a*, and the spring F acted upon from the spring E, through the medium of the disk or plate C' and its hub *a'*. The central spring, E, is controlled by the springs D F, through the intervention of the disks or plates C C', and the three springs, when the shaft A is turned in the proper direction, will be wound up, each one to a certain extent having an independent action according to its tension, and still all so connected as to be wound up simultaneously, and when wound up exert their power in a uniform combined manner on the shaft A, the power of the two springs F E being transmitted to the spring D, which is attached to the shaft A, through the medium of the disks or plates C C' and their hubs *a a'*. Any number of springs may be thus combined, a corresponding number of disks or plates C C' being employed, and by this simple arrangement a prolonged or lasting spring motor for driving machinery may be obtained within a quite limited space, and one which will act as long as each individual spring, multiplied by the number of springs used. For instance, if three seven-day-clock springs be used, the three springs will act twenty-one days, with a power equal to that of one spring, and a seven-day clock may be converted into a twenty-one-day clock without changing the gearing.

Having thus described my invention, what I claim as new, and desire to secure by Letters Patent, is—

The combining or connecting together of a series of springs in the manner substantially as herein described, so that said springs will be wound up simultaneously by the turning of a common shaft, and when wound up be made to exert their power or act in a uniform combined manner upon said shaft, as set forth.

GEORGE TERRY.
